Palmer Cox.

UNITED STATES PATENT OFFICE.

PALMER COX, OF NEW YORK, N. Y.

DESIGN FOR A HANDKERCHIEF.

SPECIFICATION forming part of Design No. 23,433, dated July 10, 1894.

Application filed February 19, 1894. Serial No. 500,794. Term of patent 14 years.

To all whom it may concern:

Be it known that I, PALMER COX, a citizen of the United States, and a resident of the city, county, and State of New York, have invented and produced a new and original Design for a Handkerchief or Similar Article of Textile Fabric, of which the following is a full, clear, and exact specification, reference being had to the drawing forming part thereof.

The object of my invention is to produce a design such as is not only new and original but also has a pleasing effect to the eye which is peculiar to itself, thus being attractive and popular.

My design as shown in the drawing is produced on woolen, silk, cotton and other fabrics.

The drawing represents a handkerchief or similar article on which is shown my design.

The leading feature of this design consists in the figure of an Uncle Sam Brownie, with hands in his pockets, which falls entire within a five pointed star having for its center, the center of the handkerchief. Standing with his feet in separate points of the star and his head in another point having an empty point on either side he seems to invite the admiration of the other Brownie figures which are grouped around as follows: First:—On one border of the handkerchief and arranged at right angles to the Uncle Sam Brownie appears an Egyptian Brownie pointing admiringly at him with his right hand. Secondly:—

On the border about in line with the Uncle Sam Brownie and on his left appears a Canadian Brownie peeping admiringly at him. Thirdly:—On the border, beneath the Uncle Sam Brownie and at right angles to him, appears an Italian Brownie pointing his left hand at him. Fourthly:—On the border, about in line with the Uncle Sam Brownie and on his right appears an Esquimaux Brownie pointing his left hand at him.

It is evident that if the leading feature of my design is dispensed with there will still remain in the figures on the border viewed with respect to each other an independent feature of my design.

The different figures are drawn to represent the characteristic dress of a peculiar country, thus serving to instruct the young, while the design affords pleasure and amusement to both young and old.

I claim—

1. The design for a handkerchief or similar article substantially as herein shown and described.

2. In the design for a handkerchief or similar article substantially as herein shown and described, the border.

PALMER COX.
